[57] **CLAIM**

The ornamental design for a combination cordless telephone handset and base, as shown and described.

DESCRIPTION

FIG. 1 is a top-front perspective view of the telephone in a vertical cradled position showing my new design; FIG. 2 is a front elevational view of the base portion of the telephone combination of FIG. 1, the handset being omitted for purposes of disclosure and convenience of illustration.

FIG. 3 is a right side elevational view of the base portion of the telephone combination in FIG. 1;

FIG. 4 is a left side elevational view of the base portion of the telephone combination in FIG. 1;

FIG. 5 is a rear elevational view of the base portion of the telephone combination in FIG. 1;

FIG. 6 is a top plan view of the base portion of the telephone combination in FIG. 1;

FIG. 7 is a top plan view of the handset portion of the telephone combination of FIG. 1, the base portion being omitted for purposes of disclosure and convenience of illustration;

FIG. 8 is a right side elevational view of the handset portion of the telephone combination in FIG. 1;

FIG. 9 is a left side elevational view of the handset portion of the telephone combination in FIG. 1;

FIG. 10 is a bottom plan view of the telephone combination of FIG. 1;

FIG. 11 is a rear elevational view of the telephone combination of FIG. 1; and,

FIG. 12 is a front elevational view of the telephone combination of FIG. 1.

The bottom plan view of the base portion of the telephone of FIG. 1 is substantially flat and unornamented and forms no part of the claimed design.

The broken lines on the handset and base are shown for illustrative purposes only and form no part of the claimed design.
